FLOOR SLAB

Edwin D. Coddington, Milwaukee, Wis., assignor
to Reynolds Corporation, New York, N. Y., a
corporation of Delaware

Application September 3, 1935, Serial No. 39,026

7 Claims. (Cl. 72—68)

This invention relates to prefabricated composition floor slabs and the like which are of simple construction and are subject to economical manufacture and which, at the same time, are strong, durable, and readily assembled in a building structure. More particularly, this invention relates to heat insulating building slabs which are capable of being incorporated into building structures by being secured to the building joist or studs by means of nails or other penetrating fastening elements. The slabs are particularly suited for use in connection with the joists and studs described in my copending applications Serial Nos. 39,023 to 39,025 inclusive; 39,027 to 39,029 inclusive; and 47,865 to 47,867, inclusive.

An object of this invention is the provision of a precast composition slab having a plain face serving as a tread surface, and which may, if desired, be covered with a strip of wear resistant material or ornamental veneer, and an undulated face, the ribs of which provide strengthening ridges extending between opposite edges of the slab.

The invention contemplates the provision of such a slab in which a reinforcing fabric is secured along the undulated surface with portions thereof imbedded within the ribs, thereby giving the elements of the slab resisting stress the maximum leverage obtainable in a slab of a given depth.

The invention further contemplates the provision of a slab composed of a cementitious material and a reinforcing fabric which possesses the property which allows it to be nailed in place while being composed of such cementitious material having slight insulating properties, has extremely high heat insulating and fire resistant properties when foil is employed in its construction.

The slab of this invention in its preferred form is non-combustible, resistant to decay and free from damage or injury by destructive insects and, when in position upon supporting joists or studs, it prevents absorption of heat by the supporting construction and the surrounding confined air with its subsequent radiation back into the room areas when the temperature therein has fallen primarily due to the incorporation of a reflective surface as a part of the reinforcing fabric. The slab also provides fire protective covering for its supporting structure.

Other objects and advantages of the invention will be apparent from the following de-

tailed description when considered in connection with the accompanying drawings wherein:

Fig. 1 is a perspective view of slabs made in accordance with this invention nailed into position upon a series of joists;

Fig. 2 is a perspective view, bottom up, of one end of the present composition floor slab illustrating the reinforcing fabric;

Fig. 3 is a vertical cross-sectional view through two abutting slabs illustrating the manner in which they are assembled in a floor structure;

Fig. 4 is a view of a portion of the slab shown in Fig. 2 but in reversed position, showing its tread surface provided with a facing of veneer; and

Fig. 5 is a perspective view of a portion of a slab made in accordance with this invention, partially broken away to show the manner of construction.

In referring to the drawings in detail the numeral 10 designates a flat block of cementitious material having a plane face 11, designed to constitute its tread surface, and an undulated face 12 adapted to form its supporting surface. The undulated face 12 provides a series of parallel longitudinally extending hills or ridges 13 separated by valleys 14. A backing sheet 15 of relatively stiff paper is bonded to the undulated surface of the block so as to completely cover this surface. Extending crosswise of and intersecting the ridges 13 at points spaced above the bottoms of the valleys 14, are a plurality of regularly spaced metal reinforcing wires 16. These wires impart strength to the block in a direction transverse to the ridges 13 but allow yielding of the slab within slight limits to preserve the characteristic "springy" property of the cementitious material which is desirable in composition floor slabs designed to take the place of wood. The cementitious composition I prefer to utilize for the manufacture of the slab comprises a wet mixture of gypsum, Portland cement and sawdust represented approximately in the proportions, by weight, 55:20:9. The material while plastic is easily molded and upon drying out it sets into a relatively hard mass. By reason of the sawdust component it possesses a "give" similar to wood and is capable of being nailed and sawed without cracking or crumbling. I have found that a nail which has been driven into a slab made in accordance with this invention resists withdrawal to a much greater extent than does a nail which has been driven into a cementitious material in which slag or shale or gritty material was used as an aggregate.

Wires 16 while acting as lateral reinforcements perform the additional function of lacing the primary reinforcement bars 17 in position upon the backing sheet 13 during the formation of the slab and in aiding in securing the backing sheet in its operative position as part of the slab.

Reinforcement bars 17 are formed as V-shaped metal strips and they are disposed between the backing sheet 13 and the series of reinforcing wires 16, the bars being embedded within and extending lengthwise along alternate ribs 13.

Relatively large wires or rods 18 are embedded within the cementitious material 10 preferably immediately adjacent the outer or tread surface thereof, and these rods, like V-shaped bars 17, extend throughout the length of the slabs into which they are incorporated whereby in the use of the slabs in the manner illustrated in Fig. 1, a contra flexure is produced as will be more fully hereinafter referred to.

To permit ready assembly of the adjacent slabs in interlocked engagement, opposite edges of the slabs parallel to the ribs 13 are cut on an offset so that two upright walls 19 and 20 connected by an inclined step 21 are formed in inverse relationship at each side of the structure. Such arrangement permits the slabs to be placed in abutting position with the extended wall 20 of one slab fitted into engagement with the reentrant wall 19 of the other slab with the walls 21 extending in overlapped relation, as illustrated in Fig. 3. Rib 13 upon the undulated face of the slab which lies adjacent the wall 19 is flattened as at 22 to insure a better registry of the undulated surfaces of the abutting slabs.

In the preferred form of slab backing sheet 13 is formed of the stiff paper as above set forth but it also comprises a thin layer of bright metal foil 23 which is affixed to its exposed surface 40 which in normal use is directed toward its supporting members. As shown in Fig. 4 when the slab is used in floor construction, the wearing surface of the slab may be protected by a facing 24 of veneer or linoleum, or the usual wooden 45 flooring, so as to present a pleasing appearance or to provide a renewable wearing surface.

The slab, because of the stiffening effect imparted by both the transverse wires and the longitudinally extending reinforcing bars and rods, 50 is exceptionally strong due to the positioning of the respective elements even when constituted of a relatively small amount of material; while the insulating property of the metallic foil, reduces heat losses resulting from absorption by and conduction of heat through the slab and into the supporting structure. Since in normal floors or walls the heat which is conducted into the supporting structure and surrounding confined air will of necessity be conducted outwardly into the 60 room space when such space has become cooler than the structure, the present slab by retarding conduction of heat into the supporting structure, overcomes the problem heretofore encountered.

The slab may be cast in any convenient sizes or 65 shapes, and, if desired, the interlocking joint described above may be provided upon all four edges of the slab, or other types of joints may be adopted.

In the formation of the slab of this invention 70 the fabric, as shown more particularly in Figure 5, is placed into the bottom of a form with the foil on its lower side. A cementitious material comprised of gypsum, Portland cement and sawdust, approximately in the proportion, by weight, 75 55:20:9 is mixed and wetted and then deposited

upon the fabric and thoroughly worked into the spaces between the wires, rods, and bars and the backing sheet in such manner that the bars and the portion of the wires which pass through the ribs are completely embedded in the cementitious material and the backing sheet due to its rigidity is firmly adhered to the cementitious material. Just prior to the filling of the form to the desired level depending upon the thickness of the slab to be produced, rods 18 are placed upon the 10 cementitious material in the form in a direction parallel to the ribs and the slab is built up to its desired thickness with the material being worked around the rods so that they are securely embedded in the finished slab near its surface opposite to the fabric. The cementitious material sets rapidly and may therefore be removed from the forms after a relatively few minutes.

The slab after curing for a short period is ready for transportation to and incorporation into a building structure. Said slab is capable of being sawed and fastened in position by penetrating elements.

In using slabs made in accordance with this invention in the manner shown in Figure 1, joists 25 24 are utilized and these joists may be fabricated in accordance with the disclosure of my copending application Serial Number 39,025. As shown the slabs are formed to extend over two spaces forming a continuous beam over three supports. 30 When placed in this manner and subjected to load there is a reversal of the bending stress over the center support which is resisted by rods 18 thus reducing the effective length of the space which the slot has to span to the distance between 35 the point of contraflexure to the joist supporting the end of the slab.

The slabs are nailed directly to the joists in a manner which will permit the abutting of adjacent slabs thereagainst both in a direction longitudinally of the joists and transversely thereof. 40

It will be understood that the preferred embodiment of the invention described above is merely exemplary and that the invention is obviously capable of embodiment in other forms 45 than that described.

I claim:

1. A prefabricated floor slab comprising a molded block of cementitious material having a plane face and an undulated face defining a series of parallel ridges, and a plurality of reinforcing members disposed adjacent the undulated face of the slab and extending crosswise of and intersecting the ridges.

2. A floor slab comprising a molded block of 55 cementitious material having a plane face and an undulated face defining a series of parallel ridges, a backing of stiff flexible material secured to the undulated face, a plurality of reinforcing members extending crosswise of and between the 60 ridges, and a plurality of rods extending parallel to the ridges and adjacent to the plane face of the slab.

3. A prefabricated floor slab comprising a generally flat molded block of cementitious material 65 having a plane face and an undulated face defining a series of parallel ribs, a backing of stiff flexible material secured to the undulated face, a plurality of reinforcing wires passing transversely through the ridges between opposite ends 70 of the block, and a plurality of reinforcement bars entirely embedded within the ribs and extending throughout the length thereof, thereby giving to the elements resisting stress the maximum leverage obtainable in the slab.

4. A prefabricated floor slab comprising a generally flat molded block of cementitious material having a plane face and an undulated face defining a series of relatively closely spaced parallel ribs, a plurality of reinforcement bars entirely embedded within the ribs and extending throughout the length thereof, a sheet of flexible material secured to the undulated face of the block and a wear strip of a different material from the slab affixed to its plane face.
5. A prefabricated floor slab comprising a generally flat molded block of cementitious material, said block being of rectangular outline and having a plane face and an undulated face defining a series of relatively closely spaced parallel ridges, a plurality of reinforcing members extending crosswise of and intersecting the ridges intermediate their height, a plurality of reinforcing bars extending within the ridges adjacent the crests thereof, one of the edges of said block having a tapered overhanging tongue coincident with the plane face of the block and the opposite
- edge of said block being provided with an undercut recess of a cross-sectional shape corresponding to the tongue whereby adjacent slabs may be assembled in interfitting relationship.
6. A prefabricated floor slab comprising a molded block of cementitious material having a plane face and an undulated face defining a series of relatively closely spaced parallel ridges, and a plurality of reinforcing bars extending within the ridges, said undulated face being substantially entirely covered with a heat reflecting material.
7. A prefabricated floor slab comprising a molded block of cementitious material having a plane face and a ribbed face, and a plurality of reinforcing wires disposed adjacent the ribbed face of the block and extending crosswise of and between adjacent ribs, said wires being located out of contact with the block intermediate the ribs.

EDWIN D. CODDINGTON.
